UNITED STATES PATENT OFFICE

GEORGE W. FLEMING, OF WORCESTER, MASSACHUSETTS, ASSIGNOR TO FLEMING MACHINE COMPANY, OF WORCESTER, MASSACHUSETTS, A CORPORATION OF MASSACHUSETTS

CUTTER

Application filed March 15, 1928. Serial No. 262,006.

This invention relates to a cutter for shaping a circular surface and is particularly adaptable for use in forming a hollow conical surface such as a valve seat.

5 The principal objects of the invention are to provide a construction in which the body of the cutter is made of material that is comparatively inexpensive and easily worked and to provide means for setting the cutting teeth 10 in this material in such a way that they are firmly fixed in place and can be ground conveniently.

Other objects and advantages of the invention will appear hereinafter.

15 Reference is to be had to the accompanying drawings in which

Fig. 1 is a side view of a complete cutter constructed in accordance with this invention;

20 Fig. 2 is an end view;

Fig. 3 is a central diametrical sectional view of the cutter;

Fig. 4 is an end view of the body of the cutter before the teeth are applied;

25 Fig. 5 is an enlarged sectional view on the line 5—5 of Fig. 4;

Fig. 6 is an enlarged sectional view on the line 6—6 of Fig. 4;

Fig. 7 is a side view of one of the cutting 30 blades;

Fig. 8 is an end view of the same;

Fig. 9 is a sectional view similar to Fig. 5 but showing the cutting blade in position; and

35 Fig. 10 is a view like Fig. 6, but showing the cutting blade in position.

The cutter is shown in a form in which it has a conical cutting surface and is designed for forming and truing valve seats, but of course, the invention is capable of use for other purposes. The cutter comprises a main body 10 consisting of a piece of sheet metal shaped to have a conical surface. The outer end is brought to a cylindrical form and a

45 cap 11 put on which projects over these ends

having a surrounding flange 12 for that purpose. A ferrule 13 is introduced through the two pieces 10 and 11 and flanged over to hold these pieces together and form a unitary structure. The ferrule is to receive a shaft 14 which is applied in any usual way.

This body 10, as well as the plate 11, is formed of soft sheet metal which can be worked in a punch or die-press and formed very rapidly. It is provided with a series of 55 slots 15 formed by slitting the metal and punching through to form flanges 16 on both sides of the slot extending through to the inner side. The slots 15 are arranged tangent to a circle concentric with the cone 10. These 60 slots extend throughout the area which is desired for cutting the conical surface.

Into each one of the slots is introduced a cutter 18. This cutter is formed of any desired grade of steel that may be suitable for the work intended and it is given a T-shape 65 as shown in Figs. 7 and 10. The long part of it at the edge is designed to form a cutting edge and the shank is provided with undercut recesses 19 on opposite sides.

When introduced in position, the ends of the flanges 16 are forced inwardly at 20 to engage in these recesses and firmly hold the shank of the cutting blade in position. At the same time the two flanges 16 are 75 forced together against the blade and the blade is forced down so that the projecting ends of the T are forced firmly against the surface of the conical part 10. In this way the blade is firmly fixed in position 80 by ordinary sheet metal working processes and it is not liable to get out of position or to rock to one side in use. These blades project from the conical surface 10 as far as may be desired and the fact that this is 85 not limited is also an advantage of this invention.

Although the blades are firmly attached, it is possible to remove one of them and replace it by hand operations, if that should 90

be found worth while. But the principal feature of the invention is that the blades can be made of fine grades of hardened steel and set in position in the holder by ordinary pressed metal operations and that the body of the support is also formed of pressed metal by simple operations.

Although I have illustrated and described only one form of the invention, I am aware of the fact that modifications can be made therein by any person skilled in the art without departing from the scope of the invention as expressed in the claims.

Therefore, I do not wish to be limited in these respects, but what I do claim is:—

15 1. As an article of manufacture, a cutter comprising a circular body of soft sheet metal having a series of slots formed therein and a series of steel blades set into said slots and firmly anchored thereto and together constituting a cutting tool, each pro-

20 jecting beyond the sheet metal body on the side opposite its cutting edge and secured firmly thereto on that side.

25 2. As an article of manufacture, a cutting tool comprising a body of sheet metal having a series of slots therein, each formed by punching through the metal and leaving two flanges on the opposite sides of the slot projecting inwardly, a cutting blade having a shank secured in said slot and projecting from the surface of the tool, said flanges being pressed against the shank of the blade to hold it in position.

30 3. As an article of manufacture, a cutting tool comprising a body of sheet metal having a series of slots therein, each having two flanges on opposite sides of the slot projecting inwardly, a cutting blade having a shank located in each slot, the shank of each tool having undercut recesses on opposite sides and the flanges projecting into said recesses to hold the blade against movement in all directions.

35 4. As an article of manufacture, a cutter comprising a circular body of soft sheet metal of hollow construction having a series of slots formed therein and a series of steel blades set into said slots, said circular body having integral means projecting from the slots into the interior of the hollow body for holding the blades.

50 5. As an article of manufacture, a cutting tool comprising a body of sheet metal having a series of slots therein, each having two flanges on the opposite sides of the slot projecting inwardly, and a cutting blade in each slot having a shank projecting from the surface of the tool and having opposite undercut recesses near its inner end, the ends of said flanges being pressed into the recesses in the shank to hold the blade in position.

55 6. As an article of manufacture, a cutting tool comprising a sheet metal body of uniform thickness throughout, having a series of

slots therein, each having two flanges on one side of the body and on opposite sides of each slot projecting from the body and a T-shaped cutting blade in each slot having the projecting ends of its top lying on the surface of the sheet metal body and its shank projecting through the body, said flanges being pressed against the shank to hold the blade in position.

70 In testimony whereof I have hereunto affixed my signature.

GEORGE W. FLEMING.
